HENRY EARL MITCHELL, OF BUFFALO, NEW YORK, ASSIGNOR TO SEMET-SOLVAY COMPANY, OF NEW YORK, N. Y., A CORPORATION OF NEW YORK

REGENERATIVE COKE OVEN AND METHOD OF OPERATING THE SAME

Application filed December 2, 1926. Serial No. 152,103.

This invention relates to by-product coke ovens particularly of the type employing long air and waste gas tunnels such as are used in the Semet-Solvay horizontal flue oven battery and to methods of operating the same, and more particularly to that feature of such ovens which deals with the manner of supplying air to the heating flues of the ovens.

The object of the invention is to establish an air feed which will furnish the requisite air to the separate heating flues in more adequate amounts and in more uniform volume per flue than has heretofore been possible and to accomplish this object in a most economical and in a substantially automatic way.

One result of the invention is to enable a greater number of ovens to be operated in conjunction with a single air system than was heretofore possible. Another result is that with a given battery the production will be increased since the ovens will complete their functions in a materially shorter time than heretofore. These and other advantages which will be referred to during the course of this specification will be obvious to those skilled in the art.

Heretofore, it has generally been deemed necessary to rely upon power driven means to propel the air to the inlet of the several heating flue systems. The air was consequently drawn in at one end of the oven battery and forced by fans or blowers to the other end (which was closed). With such a system it is obvious that the capacity of the fan controlled the capacity of the battery of ovens because the battery could not be extended beyond the distance to which the forced air draft penetrated. This limited the number of coking ovens which could make up a battery of such ovens. Even when the number of ovens was duly limited, the supply of air was non-uniform and the ovens most remote from the blower received a differentially modulated air supply than the other ovens in the series.

According to the present invention the fan or blower may be dispensed with and instead thereof an air passage freely open to the atmosphere at both ends of the battery (i. e. having ports located on opposite sides of the

transverse median line of said air passage), and, therefore, constantly full of a plentiful supply of air, may serve as a never failing air reservoir from which all of the intakes of the heating flues of all the ovens constituting the battery may at all times draw air plentifully and uniformly. The chimney draft which removes the waste products of combustion from the heating flues of all of the ovens is relatively uniform in its action on the flues of the several ovens as contrasted with the marked differential effect of a fan, and, consequently, when the chimney draft is relied on as the sole force for establishing circulation through the heating flues of the entire battery system and said flues are all in communication at their air admission inlets with a plentiful supply of air free from an artificially applied pressure, the whole battery of ovens will function more uniformly and more efficiently.

In accordance with my invention I provide a by-product coke oven battery having long air and waste gas tunnels with an air supply system having a plurality of air ports incorporated therein at various positions so as to supply an adequate amount of air to support combustion of fuel in each of the heating flues of each oven and to cause distribution of the said air supply in such a manner that the proper amount of air flows to each heating flue no matter where the flue is located in the oven battery. By incorporating these features in a coke oven structure, I am able not only to operate said structure to better effect, more economically, uniformly and speedily, but I am able to operate successfully a battery comprising a greater number of ovens than one which has limits imposed thereon by the use of a fan at a sole central intake.

My invention will be best understood by a description of an illustrative and typical example taken in conjunction with the accompanying drawings, in which: Fig. 1 shows a sectional view transverse to coke ovens embodying my invention and taken on the line 1—1 of Fig. 2; Fig. 2 is a sectional view taken on line 2—2 of Fig. 1; Fig. 3 is a sectional view taken on the line 3—3 of Fig. 1; and Fig. 4 shows an elevational view, partly in

section, on line 4—4 of Fig. 1, of the right hand side of the battery of coke ovens shown in the drawings.

In the drawings the letter S designates coking ovens which are arranged parallel to each other between bulkheads T so as to constitute a battery of coke ovens. Interposed between adjacent ovens is a division wall U which gives rigidity to the structure. A system of heating flues V, herein depicted as horizontal zigzag flues, are positioned in the usual manner between the sides of each oven and the contiguous division walls. Under each oven and parallel thereto is a heat economizing system of any well known type such as regenerators W which alternately preheat the incoming cold air and abstract heat from the outgoing hot waste products of combustion. These regenerators are connected to main gas passages or tunnels N and O by conduits X which extend from the lower portion of the regenerators to the upper portion of each of the main gas passages. A partition Y definitely separates the main passages or tunnels N and O, while the main passages N and O are themselves divided by apertured partitions Y' to define auxiliary passages N' and O'. A plurality of spaced apertures A' (see Fig. 2) may be so spaced and varied in size as to secure a uniform and adequate air supply throughout the main passages N and O. Adits whereby atmospheric air may enter the auxiliary passages N' and O' are provided at their ends (i. e. on opposite sides of the transverse median line of said auxiliary passages). In the drawings these adits at one end of the auxiliary passages, are indicated by the valve ports G and K. At the other end, the adits for air to the auxiliary passages are formed by the spaces between the ends of the partition walls Y' and the end wall of the oven. The main passages are in communication via channels Q and R with a common stack flue Z which leads to a stack or chimney P.

In order to control the communication between passage or tunnel N and flue Z and the communication between passage or tunnel O and flue Z, a main damper A is interposed between the former members and a main damper B between the latter members. These dampers are connected together by any suitable means such as a cable 1 which makes a frictional contact with idler pulleys 2 and a driving pulley 3. When one damper is in a raised position, as damper A in the drawings, a communication is established between one of the gas passages, such as N and the stack flue Z. The draft or suction of the chimney P sucks the valves or doors C and D inwardly to close ports G and H, and thus to close the main and auxiliary passages N and N' respectively, to the atmosphere. Hot waste products of combustion from the regenerators above passages N and N' pass through these passages and then go to the chimney. Simul-

taneously, air is sucked in through passages O and O' via ports J and K respectively due to the fact that valves or doors E and F are operatively connected to doors D and C respectively and are open to the atmosphere when doors D and C are closed. These doors may be connected in any appropriate manner such as with cables 5 running in pulleys 6, each of the latter being supported by a combination door stop and bracket 7. The door stop holds each door or valve at a suckable angle so that each door may be drawn in quickly and tightly when subjected to the suction of the chimney. In this connection it will be observed that while the chimney suction causes a pressure on both sets of valves, CD and EF, there is a pressure differential, or a greater pressure, on the valves CD when the damper A is raised due to the direct air passage leading to the chimney, and this differential is utilized for opening the valves EF by means of the cables 5 connecting the valves CD with the valves EF. In addition, it may be further noted that there is a moving column of air exerting pressure on the open valves to close them when the corresponding damper is opened, while the closed valves are under a static pressure.

At the other end of the battery of ovens adjacent to the stack, I provide air ports L and M which may be closed by a slide valve 8. This valve slides in guides 9 positioned at each side thereof and has a rack 10 secured to its upper surface. A pinion 11 keyed to shaft 12 coacts with rack 10 and causes the latter and the associated valve 8 to move back and forth. The shaft 12 may be supported in any customary manner and is rotated by a sprocket gear 13 secured thereto which is driven by a chain 14 and a driving sprocket gear 15. When the driving pulley 3 rotates in one direction it raises damper A from a closed position to an open position, as herein illustrated. Driving sprocket gear 15 rotates with pulley 3 and drives sprocket gear 13 through the medium of chain 14. Pinion 11 being geared to the same shaft as sprocket gear 13 rotates therewith and moves valve 8 from air port M to L by its coactions with rack 10. In the aforesaid manner the operation of the main driving gear 3 by well known automatic means (not shown), not only operates main dampers A and B but actuates the valves controlling the air ports. Thus, when damper A is raised to establish a communication between the stack P and passage N and N', air port L is closed by valve 8 and air ports G and H are closed by valves C and D. Simultaneously, air port M is opened and air ports J and K are likewise opened. By the reversal of the gas flow, main damper B is raised, air port M is closed by the rack and pinion mechanism, and air ports J and K are closed by valves E and F respectively which are sucked in by the draft or suction of the

chimney. When these operations occur air ports L, G, and H are opened simultaneously and automatically with the closing of the other set of air ports.

5 The method of operating by-product coke ovens in accordance with my invention or a battery of ovens having my improved air control means incorporated therein is readily obvious to one skilled in the art. The coking chambers are charged and sealed in the usual manner. Air is admitted simultaneously at each end of the battery of coke ovens to the long gas passages as indicated by the arrows in passages O, O' (Figs. 1 and 2) and thence 10 to the regenerators wherein the cold incoming air is preheated. The frictional resistance to the flowing air is reduced substantially because the air path only extends from one end of the battery to about the middle thereof, whereas heretofore the air path extended from one end of the battery to the other end thereof. Due to these relatively short air paths and to the absence of unevenly applied 15 pressure, there is a substantially even distribution of air to all of the regenerator units. The preheated air from the regenerators flows to the heating flues in the usual manner wherein the said air supports combustion of the fuel admitted from burners positioned 20 in the flue system. The products of combustion resulting from the burning of the fuel pass through the heating flues into another set of regenerators which abstract heat from the hot waste gases before the latter pass as a 25 common stream to the chimney as indicated by the arrows in passages N, N' (Fig. 2). At the termination of a period the gas flow is reversed in a well-known manner. Air now 30 flows to the second set of regenerators which were heated by the hot products of combustion of the prior period. The ports through 35 which the air enters the battery to the second set of regenerators are likewise positioned at each end of the battery so that the incoming air flows from each end toward the middle 40 of the battery. The preheated air flowing from the regenerators supports combustion of the fuel in the heating flues, and the resulting 45 products of combustion flow as a common stream to the chimney as described above.

In the operation of the embodiment of my invention illustrated herein, the dampers A and B are so balanced that whenever one damper is in a raised position the other damper is in a down position. When A is in the raised position as shown the related air ports L, G, and H are closed and at least some of the ports are closed by the suction of the stack. Under certain conditions, however, the valves on all the air ports at each end of the battery may be operated by the suction of the stack, for instance, in the embodiments illustrated in the drawings, valves controlling air ports L and M may be pneumatically operated as 55 well as air ports G, H, J, and K. The air

ports M, J, and K related to damper B are opened simultaneously and automatically with the closing of the other set of air ports G, H, and L. In other words, the air ports connected to one set of gas passages (for instance O and O') are arranged to admit air to their respective flues when the related main damper (for instance B) is set to close the communication between the set of passages and the stack flue, whereas the air ports connected to the other set of passages being arranged to shut off the air to their respective flues when their related damper is set to open the communication between the last set of passages and the chimney. This arrangement provides a very effective method of controlling the flow of cold air to the regenerators and the flow of hot waste products of combustion to the stack, as well as reversing or alternating the gas flow through the gas circulation system of the battery of ovens.

It will be noted that my invention provides means which can be easily incorporated in existing by-product coke oven batteries without substantial changes. Coke oven batteries which have been provided with my air control mechanism operate without the use of air fans and produce more coke and by-products per week or month than heretofore, i. e. the number of ovens pushed per time unit from each battery has been increased.

It will be further observed that when my invention is embodied in a new battery of by-product coke ovens a greater number of ovens may be incorporated in a battery under the same conditions than formerly or a greater number of ovens can be pushed per week or month from a battery containing the same number of ovens as in structures of the prior art.

Furthermore, when a battery of by-product coke ovens is operated in accordance with my invention, a relatively flexible system of production is available. This flexibility which permits operating the ovens at higher than rated capacity without the use of excessive quantities of fuel gas and without loss of by-products is due in large part to the more uniform heating throughout the oven battery occasioned by the more even distribution of the air.

Although I have shown certain types of valves, operating mechanism, etc., it is obvious that various modifications may be made without departing from the scope and spirit of the invention.

I claim:

1. In a battery of by-product coke ovens comprising a series of alternate coking chambers and heating walls therefor arranged side by side, each of said heating walls comprising heating flues and regenerator sets in communication with said heating flues, that improvement which comprises air passages extending from one end of the battery to the other end

of the battery, and communicating with each set of regenerators, sets of air ports in the walls at the opposite ends of said passages communicating therewith, and means operatively associated with each of said sets of air ports to put the latter in or out of communication with the air, each of said passages being adapted to be simultaneously opened or closed to the air at opposite ends of the battery.

2. In a battery of by-product coke ovens comprising a series of alternate coking chambers and heating walls therefor arranged side by side, each of said heating walls comprising heating flues and regenerators in communication with said heating flues, and having two pairs of gas passages, each of said pairs of gas passages comprising a main gas passage and an auxiliary gas passage communicating therewith, each passage extending from one end of said battery to the other end and each of the main gas passages being communicably connected with the regenerators and a stack flue joining the two main gas passages with a stack, that improvement which comprises a wall at one end of the battery having air ports communicably connected to said main gas passages adjacent the stackflue, means operatively associated with the ports whereby the port of one of the main gas passages may be put into communication with the air and the port of the other main gas passages may be simultaneously closed to the air, said battery having an air port connected to each gas passage in the wall at the other end of the battery, and means controlling the second mentioned set of air ports whereby the ports connected with one pair of gas passages may be put into communication with the air when the ports connected with the other pair of gas passages are closed to the air, each of said main gas passages being adapted to be simultaneously opened or closed to the air at opposite ends of the battery.

3. In a battery of by-product coke ovens comprising a series of alternate coking chambers and heating walls therefor arranged side by side, each of said heating walls comprising heating flues and regenerator sets in communication with said heating flues, and having gas passages extending under the battery from one end to a stack flue at the other end and communicably connected with the regenerators, said battery having air ports in the walls of said passages at the ends of the battery communicating with said passages, a main damper in each gas passage adjacent to said stack flue for controlling the communication between said passages and the stack flue, valve means for the air ports, means controlled by the dampers whereby the air port connected to one gas passage adjacent to said stack flue may be put into communication with the air when the damper in said passage closes the communication between

said passage and the stack flue, and simultaneously with the aforesaid operations the other main damper establishes the communication between the other gas passage and the stack flue and automatically therewith closes the communication between the other air port associated with said last gas passage adjacent to said stack flue and the atmosphere.

4. In a battery of regenerative by-product coke ovens, comprising a series of alternate coking chambers and heating walls therefor arranged laterally of each other in a row, each of said heating walls comprising combustion flues, in combination, a stack, two sets of gas passages extending from one end of said battery to the other, each of said sets comprising a main gas passage and an auxiliary gas passage communicating therewith, the main gas passages being communicably connected to the flues, a stack flue joining said main gas passages with said stack, a main damper for controlling and alternating the flow of gas from said sets of gas passages to said stack, and air ports in the walls of said battery for communicably connecting each of said sets of passages with the atmosphere, the ports connected to one of said main gas passages being arranged to admit air through both ends of the same to flues communicably connected therewith when the main damper is set to close the communication between the main gas passage and the stack flue, the ports connected to the other main gas passage being arranged to shut off the air to the flues communicably connected therewith when the main damper is set to open the communication between said other main gas passage and the stack flue.

5. In a battery of regenerative by-product coke ovens comprising a series of alternate coking chambers and heating walls therefor, arranged laterally of each other in a row, each of said heating walls comprising combustion flues, in combination, a stack, two sets of gas passages extending from one end of said battery to the other, each said sets comprising a main gas passage and an auxiliary gas passage communicating therewith, the main gas passages being communicably connected to the flues, a stack flue joining said main gas passages with said stack, a damper individual to each of said main gas passages for controlling and alternating the flow of gas from said sets of gas passages to said stack, air ports in the walls of said battery for communicably connecting each of said passages with the atmosphere, the ports connected to one of said main gas passages being arranged to admit air through both ends of the same to the flues communicably connected therewith when the damper individual thereto is set to close the communication between the aforementioned one of said main gas passages and the stack flue, the ports con-

- nected to the other main gas passage being arranged to shut off the air to the flues communicably connected therewith when the damper individual thereto is set to open the communication between said other main gas passage and the stack flue, and means operatively connecting the dampers and the air ports so that when one damper closes the communication between one of said main gas passages and the stack flue, the other damper simultaneously establishes the communication between the other main gas passage and the stack flue and the air ports connected to the aforementioned one of said main gas passage and to the auxiliary gas passage communicating therewith are adapted to be put into communication with the atmosphere, whereas the air ports connected to the other main gas passage and to the auxiliary gas passage communicating therewith are adapted to be simultaneously put out of communication with the atmosphere.
6. In a battery of regenerative by-product coke ovens comprising a series of alternate coking chambers and heating walls therefor, arranged laterally of each other in a row, each of said heating walls comprising combustion flues, in combination, a stack, two sets of gas passages extending from one end of said battery to the other, each of said sets comprising a main gas passage and an auxiliary gas passage communicating therewith, the main gas passages being communicably connected to the flues, a stack flue joining said main gas passages with said stack, a damper individual to each of said main gas passages for controlling and alternating the flow of gas from said sets of gas passages to said stack, air ports in the walls of said battery for communicably connecting each of said passages with the atmosphere, the ports connected to one of said main gas passages being arranged to admit air through both ends of the same to the flues communicably connected therewith when the damper individual thereto is set to close the communication between the aforementioned one of said main gas passages and the stack flues, means connecting the dampers to each other so that when one is in a closed position the other is in an open position, a reciprocating valve controlling the air ports at one end of the battery, and means operated by the movement of said dampers for actuating said reciprocating valve.
7. In the method of operating a regenerative battery of by-product coke ovens comprising a series of alternate coking chambers and heating walls therefor arranged laterally of each other in a row, each of said heating walls having horizontal heating flues incorporated therein, regenerators communicably connected with the heating flues and gas passages communicably connected with the regenerators, each passage extending un-
- der the battery from one end to the other, the steps which comprise burning fuel in the heating flues and simultaneously admitting air to some of the regenerators through the gas passages from each end of the battery to support combustion of the fuel in the heating flues.
8. The method of operating a regenerative battery of by-product coke ovens involving a series of alternate coking chambers and heating walls therefor arranged laterally of each other in a row, each of said heating walls comprising combustion flues, regenerators communicably connected with the combustion flues, gas passages, each of which extends from one end of the battery to the other end and is communicably connected with the regenerators and with a stack flue, the walls of the gas passages having ports for the admission of air thereinto which comprises burning fuel in the combustion flues and shutting at least one of the air ports connected to one of the passages by the suction of the stack, and simultaneously therewith opening at least one of the air ports connected to another of the passages.
9. In a regenerative coke oven battery, in combination a series of alternate coking chambers and heating walls therefor arranged laterally of each other in a row, each of said heating walls being provided with horizontal heating flues, regenerators communicating with the heating flues, two pairs of air and waste gas passages therebeneath connected for alternate supply of air to the regenerators for feeding the heating flues and removal of waste gas from the regenerators, each of said pairs comprising a main gas passage and an auxiliary gas passage communicating therewith, said battery having an air opening in the walls of each of the main gas passages communicating therewith at one end of the battery, an air port in a wall of each of the main gas passages and the auxiliary gas passages communicating therewith at the other end of the battery, a door for each of the air ports, a member joining the doors to cause the doors for the air ports of one pair of passages to be closed while holding the doors for the air ports of the other pair of passages open, a mechanism for alternately opening and closing each air opening, a stack and a mechanism for putting one pair of passages in communication with the stack and for creating a suction alternately in said pairs of passages sufficient to close the doors for the air ports in one pair of passages while holding the doors for the air ports in the other pair of passages open.
10. In a regenerative battery of coke ovens comprising a series of alternate coking chambers and heating walls therefor arranged laterally of each other in a row, each of said heating walls being provided with heating

flues, regenerators in communication with the heating flues, a main air passage extending from one end of the battery to the other and air ducts communicably connecting the regenerators with said main air passage, said battery having a plurality of ports in the walls thereof spaced from each other, each in communication with the main air passage and with the atmosphere, said ports being located respectively on opposite sides of the transverse median line of the main air passage.

11. In a battery of by-product coke ovens comprising a series of alternate coking chambers and heating walls therefor arranged laterally of each other in a row, each of said heating walls being provided with heating flues, regenerators in communication with the heating flues, a main air passage communicably connected with the regenerators, said battery having a plurality of ports in the walls thereof spaced from each other, each in open communication with the main air passage and with the atmosphere, said ports being located on opposite sides of the transverse median line of said main air passage so as to admit atmospheric air separately through said spaced ports on opposite sides of the transverse median line to the main air passage in the neighborhood of at least one of the two ends of the main air passage, an auxiliary air passage communicably connected with said main air passage, and adits in the walls of said battery on opposite sides of the transverse median line of said auxiliary air passage for admitting air to said auxiliary air passage.

12. In a battery of regenerative by-product coke ovens embodying the combination set forth in claim 9, in which the doors for the air ports are adapted to be closed by the stack suction and in which means is provided for causing the doors in their return movement toward an open position to be stopped in a position in which they are responsive to the closing effect of said stack suction on subsequent reversal of gas flow through the battery.

13. The method of operating a battery of by-product coke ovens having a series of alternate coking chambers and heating walls therefor arranged laterally of each other in a row, each of said heating walls comprising heating flues, which method comprises burning fuel in the heating flues, alternately feeding air from one of two paths to the heating flues while sending products of combustion from the heating flues through the other of said two paths and supplying each of said paths with atmospheric air at each of its ends during every period of air flow thereinto.

14. The method of operating a battery of by-product coke ovens, having a series of alternate coking chambers and heating walls therefor arranged laterally of each other in

a row, each of said heating walls comprising heating flues and a chimney for the battery, which method comprises burning fuel in the heating flues, leading hot products of combustion of the fuel in the heating flues from each separate set of the flues into a common stream and thence causing said stream to flow to the chimney, periodically leading the hot products of combustion from each separate set of said flues into a second independent common stream, and always establishing free communication with the atmosphere for incoming air at both ends of the path defined by that one of the two aforesaid common streams which is not being traversed by the hot products of combustion, and feeding air from said path to the heating flues.

15. The method of operating a battery of by-product coke ovens having a series of alternate coking chambers and heating walls therefor arranged laterally of each other in a row, each of said heating walls comprising heating flues and a chimney for the battery, which method comprises burning fuel in the heating flues, transferring heat from the hot products of combustion of the fuel in the heating flues to independent heat absorbers, then leading the products of combustion from each of such absorbers into a common stream, and thence causing said stream to flow to the chimney, periodically transferring heat from the hot products of combustion to a second set of heat absorbers and leading the resultant products of combustion from each of said absorbers into a second common stream and thence causing said stream to flow to the chimney, and always establishing free communication with the atmosphere for incoming air at both ends of the path defined by that one of the two aforesaid common streams which is not being traversed by the products of combustion, and feeding air from said path to the heating flues.

16. The method of operating a battery of by-product coke ovens, having a series of alternate coking chambers and heating walls therefor arranged laterally of each other in a row, each of said heating walls comprising heating flues and a chimney for the battery, which method comprises burning fuel in the heating flues, leading hot products of combustion of the fuel in the heating flues from each separate set of the flues into a common stream and thence causing said stream to flow to the chimney, periodically leading the hot products of combustion from each separate set of the flues into a second independent common stream, and always establishing free communication with the atmosphere for incoming air at both ends of the path defined by that one of the two aforesaid common streams which is not being traversed by the hot products of combustion, and feeding air from said path to the heating flues, establishing a chimney suction and causing said suc-

tion to impart the movement of the gas flow involved in the conduct of the aforesaid steps.

17. In a battery of by-product coke ovens having a series of alternate coking chambers and heating walls therefor arranged side by side, each of said heating walls comprising heating flues, regenerators in communication with the heating flues, a main air passage communicably connected with the regenerators and battery walls having a plurality of ports spaced from each other, each port being in communication with the main air passage and with the atmosphere, said ports being so located as to admit atmospheric air through said spaced ports to the main air passage in the neighborhood of at least each of the two ends of said main air passage.

18. In a battery of by-product coke ovens having a series of alternate coking chambers and heating walls therefor arranged side by side, each of said heating walls comprising heating flues, an air passage extending from one end of the battery to the other end, ports located in the walls of said passage so as to admit atmospheric air thereto adjacent the two ends thereof and regenerator sets in communication with said air passage and said heating flues.

In testimony whereof I have hereunto set
30 my hand.

HENRY EARL MITCHELL.
